FUR BUFFING MACHINE

Francis Luckower, Mount Vernon, N. Y.

Application October 15, 1947, Serial No. 780,051

13 Claims. (Cl. 69—27)

1

This invention relates to the treatment of fur and has special reference to the ironing, buffing, and combing of fur garments.

In what may be termed the rejuvenation of the fur in fur garments, the object is to restore, after its original treatment in the pelt to its pristine condition wherein the fur remaining on the pelt has its hairs disposed in regularly arranged condition. The hairs in fur garments, through use, tends to form a matted condition and the hairs do not lie in their original relation. The terms "glazing" and "electrification" are understood by furriers to mean the causation of the hairs to stand in regularly spaced positions away from the pelt. The term "buffing" is understood by furriers to consist in ironing the fur, while in a dampened condition, so that the hairs are restored to their original and sometimes interlocking relationship.

The present invention contemplates the achievement of both of these objects and it is herein preferred to use the term "buffing" to indicate the freeing of the separate hairs from adhesion to each other and the term "combing" for arranging such hairs in their normal relationship.

With the above in mind, it is the principal object of the present invention to produce a novel and highly effective fur ironing device whereby furs, whether in garments or not, may be successfully buffed with the buffing operation accompanied in some instances by combing to cause the hairs of the fur to lie parallel or substantially so.

Another important object of this invention is to provide a novel instrumentality to accomplish the foregoing purposes in the shape of an electrically heated iron.

Ironing devices carrying a heated ironing surface and having a following or trailing comb have heretofore been used. Such devices are, however, insufficient since they press the fur hairs against the pelt and mat them together, which matting is not properly cured by the subsequent combing.

A further object of this invention is to provide a novel arrangement of fur treating iron whereby a fur may be simultaneously buffed and combed so that all matting of the fur is avoided.

A still further object of the invention is to provide a novel shape of fur ironing mechanism whereby all parts of a fur garment may be treated without the need of separating such parts by upping and restitching.

Again, another object of the invention is to provide a machine whereby ironing, buffing, and combing will be accomplished without injury to the fur or loss of hair therefrom.

With the above and other objects in view, as will be presently apparent, the invention consists

2

in general of certain novel features of construction and combinations of parts hereinafter fully described, illustrated in the accompanying drawings, and particularly claimed.

In the accompanying drawings like characters of reference indicate like parts in the several views:

Figure 1 is a front elevation of a table-supported machine constructed in accordance with this invention.

Figure 2 is a side elevation thereof.

Figure 3 is an enlarged detail section of Figure 4 but showing a manually operated form of the device.

Figure 4 is an enlarged detail section of the head shown in Figure 1 on the line 4—4 thereof.

Figure 5 is a section on the line 5—5 of Figure 4.

Figure 6 is a fragmentary detail of the section shown in Figure 5.

Figure 7 is a second fragmentary detail of construction shown in Figure 6.

Figure 8 is a section on the line 8—8 of Figure 7.

Figure 9 is a further modification of the section shown in Figure 6.

Figure 10 is a section on the line 10—10 of Figure 9.

Figure 11 is a fragmentary front elevation of a modified form of ironing head employing a rib-like buffer.

Figure 12 is a side elevation of the device as disclosed in Figure 11.

Figure 13 is a fragmentary front view partly in section and showing a toothed modification of Figure 11.

Figure 14 is a side view of the device as shown in Figure 13.

Figure 15 is a front elevation of an ironer head employing a spirally grooved buffer element, and Figure 16 is a side elevation of Figure 15.

In the embodiment of the invention shown in Figures 1 and 2 there is provided a table 10 whereon is mounted a frame 11 supporting a housing 12 having a rear bearing 13 and a forward bearing 14. A shaft 15 is journaled in these bearings and carries at its rear end a belt pulley 16 connected by a belt 17 to the belt pulley of a motor 18 the operation of which is regulated by a controller 19.

In the form shown in Figure 3, a construction is disclosed suitable for use as a hand tool. Here the long shaft 15 is supplanted by a shorter shaft 20 to the rear end of which is pinned a flexible shaft 21 driven by any suitable motor (not shown). The flexible shaft is housed in a flexible cover 22 carrying a bearing 23 in which shaft 20 is journaled and also having a hand grip 24.

In each case brackets 25 are provided which

60 carry suitably insulated brush holders 26 and on

the shaft is mounted a pair of insulated contact rings 27 engaged by brushes in said holders. A hood 28 covers and protects these parts and wires 29 conduct current to the brush holders.

In all forms of the invention there is provided a head indicated in general at H of generally conoidal form. The head has a hollow inner shell 30 fixed to the end of the shaft. On this shell is mounted a heating element 31 connected by wires 32 with the rings 27. An outer shell or cover 33 fits over the heating element and is screwed on the extremity of the shaft, thus securing the heating element firmly in position.

Each of the forms of this invention is provided with buffing means. In the form shown in Figures 1, 2, 4, and 5 this buffing means consists of one or more V-shaped longitudinally extending grooves. Each groove has a radial side 34 and a side 35 at an acute angle thereto. In this and all other forms the device is rotated in the direction of the arrow A so that the edge formed by the intersection of the face 34 with the outer face of the shell 33 repeatedly strikes the fur as the head rotates.

The form shown in Figure 6 has a like groove with a radial side 34 and inclined side 35 but in this form a wear plate 36 is fitted against the radial side 34 so the buffing edge may be kept in the necessary condition for buffing, this wear plate being replaceable when worn.

In the form shown in Figures 7 and 8 the groove has the sides 34 and 35 but a toothed wear plate 37 is fitted against the side 34. This construction provides for a combing action in addition to the buffing.

In the form just described, the teeth of the wear plate terminate flush with the outer surface of the shell 33 but, as shown in Figures 9 and 10, the teeth of a toothed wear plate 38 project beyond the outer surface of shell 33. This affords a somewhat increased combing action.

In the form shown in Figures 11 and 12 the buffing is done by smooth longitudinal ribs 39 and in the form of Figures 13 and 14 by toothed ribs 40.

In the form shown in Figures 15 and 16 the V-shaped groove with a radial face 34 and an inclined face 35 is used but the grooves extend in a sinuous manner along the head H.

What is claimed is:

1. In a fur ironing machine, a conoidal fur-engaging member having at least one external fur buffing means, heating means within said element, and means rotating said element.

2. In a fur ironing machine, a conoidal fur-engaging member having at least one external fur buffing and combing means, heating means within said element, and means rotating said element.

3. In a fur ironing machine, a conoidal fur-engaging member having at least one external fur buffing means, heating means within said element, and means rotating said element, said buffing means being flush with the surface of said member.

4. In a fur ironing machine, a conoidal fur-engaging member having at least one external fur buffing and combing means, heating means within said element, and means rotating said element, said combing means extending beyond the surface of said member.

5. In a fur ironing machine, an outer substantially conoidal member, an inner substantially conoidal member spaced inwardly from said outer

member, buffing means on the peripheral face of the outer member, an electrical heating element interposed between said members, means to supply heating current to said element, and means to rotate said members and element.

6. In a fur ironing machine, an outer substantially conoidal member, an inner substantially conoidal member spaced inwardly from said outer member, buffing means on the peripheral face of the outer member, including a wear plate taking the wear on said buffing means, an electrical heating element interposed between said members, means to supply heating current to said element, and means to rotate said members and element.

15. 7. In a fur ironing machine, a conoidal fur-engaging member having at least one external fur buffing means, heating means within said element, and means rotating said element, said buffing means extending sinuously along said conoidal member.

18. 8. In a fur ironing machine, a conoidal fur-engaging member having at least one external fur buffing means, heating means within said element, and means rotating said element, said conoidal member housing a base and a blunt point and said buffing means terminating at its ends in spaced relation to said base and point.

9. In a fur ironing machine, a conoidal fur-engaging member having at least one external fur buffing and combing means, heating means within said element, and means rotating said element, said combing means consisting of teeth projecting outwardly from the surface of said conoidal member.

35. 10. In a fur ironing machine, an outer substantially conoidal member, an inner substantially conoidal member spaced inwardly from said outer member, buffing means on the peripheral face of the outer member, including a wear plate taking the wear on said buffing means, said wear plate having teeth projecting beyond the surface of said conoidal member, an electrical heating element interposed between said members, means to supply heating current to said element, and means to rotate said members and element.

11. In a fur ironing machine, a conoidal fur-engaging member having at least one external fur buffing means, heating means within said element, and means rotating said element, said buffing means including a groove formed in the surface of said member and having a radial face located on the trailing side of said groove.

12. In a fur ironing machine, a conoidal fur-engaging member having at least one external fur buffing means, heating means within said element, and means rotating said element, said buffing means including a groove formed in the surface of said member and having a radial face located on the trailing side of said groove and having a wear plate fixed to said trailing side.

13. In a fur ironing machine, a conoidal fur-engaging member having at least one external fur buffing means, heating means within said element, and means rotating said element, said buffing means including a groove formed in the surface of said member and having a radial face located on the trailing side of said groove and having a wear plate fixed to said trailing side and provided with teeth projecting radially from said member.

14. In a fur ironing machine, a conoidal fur-engaging member having at least one external fur buffing means, heating means within said element, and means rotating said element, said buffing means including a groove formed in the surface of said member and having a radial face located on the trailing side of said groove and having a wear plate fixed to said trailing side and provided with teeth projecting radially from said member.

FRANCIS LUCKOWER.
